MEANS FOR TREATING THREAD OR
THE LIKE

Lavern J. Jordan, Fairview Village, Ohio, assignor
to Industrial Rayon Corporation, Cleveland,
Ohio, a corporation of Delaware

Application September 12, 1939, Serial No. 294,455

5 Claims. (Cl. 34—153)

This invention relates to means for subjecting thread or the like (hereinafter referred to as "thread") to the action of a temperature-changing fluid while it is being continuously but temporarily stored in generally helical form. By "temperature-changing fluid" is meant, inter alia, such media as steam, hot water or oil which are capable of transferring heat without being permitted to come into physical contact with the thread as well as heated gases such as air that are discharged directly upon the thread itself. It is also intended to apply to certain media capable of reducing the temperature of thread for the purpose, for example, of controlling the rate of reaction of a chemical process occurring in or on the thread.

In general, the invention contemplates an improved apparatus for subjecting thread while it is continuously but temporarily stored in generally helical form as, for example, upon a thread-advancing thread store device to the action of a greater quantity of temperature-changing fluid toward one end of said device than toward the other. The thread-advancing thread store device is advantageously of the type having a plurality of rotatably supported thread-manipulating elements and in accordance with the invention provision is made for introducing the temperature-changing fluid to the interior of at least one of the thread-manipulating elements; this thread-manipulating element is also so constructed and arranged as to supply temperature-changing fluid adjacent to the point at which the thread is first applied to the periphery of the device in a quantity greater than that which is supplied adjacent to a point at which the thread is removed from the device.

For convenience, the invention will be described hereinafter as it has been employed in the drying of moist thread upon a thread-advancing thread store device taking the form of a thread-advancing reel.

Among other things, thread-advancing thread store devices within the purview of the invention are characterized by means providing that the heat, and therefore the drying conditions, to which the thread is subjected, is more intense over the portion of the device handling relatively wet thread than over the portion of the device handling relatively dry thread. In other words, the temperature to which the thread is heated, and therefore the rate at which the thread is dried, is greatest at the beginning of the drying operation. Preferably, however, the heat is applied in such manner that its intensity varies

progressively lengthwise of the device, being greatest on the portion of the device at which the thread is wettest and least on the portion of the device at which the thread is driest.

Subjecting the thread to the greatest amount of heat and highest temperature on the portion of the device at which the thread has the highest moisture content and to less heat and lower temperatures on the portions of the device where the thread has lower moisture contents makes for a greater degree of uniformity in the drying of the thread. It also decreases the possibility of damage to the thread, which, as the moisture content decreases, becomes more susceptible to damage from heating to excessively high temperatures. More efficient drying of the thread can be obtained by means of the present invention, a factor which is extremely advantageous in the continuous drying of thread, due to the shortness of the time permitted for the drying of the thread in a continuous process.

Apparatus of the type embraced by the invention and capable of carrying out the thread-drying operation comprises a thread-advancing thread store device embodying, among other things, two spaced thread-advancing elements which, during rotation of at least one thereof, cooperate to wind the thread into a traveling spiral consisting of a plurality of generally helical turns. By way of illustration, reference will be made to three types of thread-advancing reels generally similar to the reel shown, described and claimed in Patent No. 2,145,281, granted January 31, 1939, to Clarence C. Walters. Each of such 30 thread-advancing reels, like the reel shown in said patent, comprises two wholly rigid reel members, the peripheries of which are made up of spaced, longitudinally extending bar members, the bar members of the two reel members being interleaved.

In the drawing, three different embodiments of the invention are shown. Figure 1 is a longitudinal sectional elevation along line 1—1 of Figure 2 of one form of drying reel heated internally by means of air. Figure 2 is an end elevation from line 2—2 of Figure 1. Figure 3 is a longitudinal sectional elevation from line 3—3 of Figure 4 of another embodiment of the invention. Figure 4 is a corresponding end elevation from line 4—4 of Figure 3. Figure 5 is a longitudinal sectional elevation of a third embodiment of the invention. Figure 6 is an end elevation thereof from line 6—6 of Figure 5. In the drawing, like reference characters refer to like parts throughout.

The embodiment of the invention shown in Figures 1 and 2 comprises a thread-advancing reel embodying two wholly rigid reel members 1 and 2. Said reel members are generally circular in cross section, each having a substantially cylindrical thread-bearing periphery made up of spaced, longitudinally extending bar members. Reel member 1 is provided with spaced, longitudinally extending bar members 3, while reel member 2 is provided with a like number of spaced, longitudinally extending bar members 4 alternating therewith. Each of said reel members is rotatably supported from a frame member 5 for rotation about its own axis. The axes of the reel member, however, are displaced from each other, being disposed in what is referred to in geometry as skew relation.

Reel member 1, which may be termed the concentric reel member, is of one-piece construction, having its bar members 3 formed integrally with a substantially cylindrical body portion 6. Said body portion 6, which is mounted on a drive shaft 7 journaled in frame member 5, is rigidly held on such drive shaft by a cap bolt 8 threaded into the end of the drive shaft. Cap bolt 8 serves to hold said body portion 6 against a pin 9 passing through drive shaft 7 projecting into a groove 10 formed in body portion 6. Driving relation is thereby provided between said drive shaft 7, which is positively rotated, and concentric reel member 1.

Reel member 2, which may be termed the eccentric reel member, is driven by contact of its bar members 4 with the bar members 3 of concentric reel member 1. Said reel member 2 is formed with its bar members 4 rigidly fixed at one end thereof to a rotatable supporting member 12 disposed at one end of reel member 1, the bar members 4 projecting from said member 12 between the bar members 3 of reel member 1. By virtue of this construction, the reel as a whole, and also the other reels described hereinafter, is of cantilever form; i. e., it is supported from one end only and has its other end unobstructed by shafting, supporting means or the like.

The bar members 4 of reel member 2 are individually formed, being disposed in holes in member 12 in which they are rigidly held by set screws 13. Supporting member 12 has rigidly fixed therein a bearing sleeve 14 by means of which it is rotatably mounted on frame member 5. The axis of rotation of supporting member 12, and hence of eccentric reel member 2, is inclined from parallelism with, but is disposed in a plane offset from and parallel to, the axis of rotation of reel member 1.

Consequently, when the reel members are rotated by rotation of drive shaft 7, each of said reel members rotates about its own axis. At the same time, the thread turns wound about said reel members are transferred at intervals from the bar members of one reel member to those of the other; that is, the thread is carried by the bar members 3 of reel member 1 over the upper half of the reel and by the bar members 4 of reel member 2 over the lower half of the reel. Simultaneously, because of the inclined relation of the axes, that portion of each thread turn carried by the bar members of each reel member is advanced lengthwise of the other reel member so that the thread as a whole advances lengthwise of the reel in a plurality of spaced, generally helical turns the spacing of which is determined by the amount of inclination between the axes of the reel members.

As in each of the several embodiments of the invention shown in Figures 1 to 6, inclusive, the thread is advanced toward the unsupported end of the reel.

In the reel of Figures 1 and 2, reel members 1 and 2 are preferably formed of some material having good heat conductivity, such as aluminum. Reel member 1 is hollow, having an interior chamber 15 into which a heated medium such as hot air passes from hollow shaft 7 through openings 16 therein. Reel member 1, being of massive construction, is heated largely by conduction; however, said reel member is also provided with a plurality of openings 17 extending radially of said reel member from said interior chamber 15 to points between the bar members 3 of said reel member. By means of said openings 17, heated air passing out of interior chamber 15 reaches the thread directly.

In the embodiment of the invention illustrated in Figures 1 and 2, openings 17 vary in size, the largest opening being nearest the supported end of the reel. The other openings decrease regularly in size as they approach the unsupported end of the reel. Therefore, the thread advanced along the reel is subjected to the most heat where the thread is wettest and to progressively less heat as it advances lengthwise of the reel, this because of the decreasing amount of heated air to which the thread is subjected. After the thread advances beyond the smallest hole 17, the heat to which the thread is subjected reaches it only by conduction, wherefore the amount of heat to which the thread is subjected is less than that to which the thread is subjected while in direct contact with the heated air issuing through openings 17.

The embodiment of the invention shown in Figures 3 and 4 is generally similar to that of Figures 1 and 2, differing therefrom primarily in that its concentric reel member 1a is provided with radially extending openings 17a disposed substantially throughout its entire length. The openings 17a are largest at the supported end of the reel, since thread having the highest moisture content is carried by this portion of the reel. As will appear from Figure 3, the openings 17a are of two sizes, being divided as shown into groups extending over the first and second halves of the thread-bearing periphery of the reel.

The reel of Figures 3 and 4 is generally similar to that of Figures 1 and 2. It comprises a reel member 1a concentrically mounted upon drive shaft 7a journaled in frame member 5a. Said reel member 1a is held on drive shaft 7a by means of a set screw 19 bearing against said drive shaft 7a and by means of a cap 20 threaded on the unsupported end of said drive shaft 7a. As in the embodiment of the invention shown in Figures 1 and 2, reel member 1a is of one-piece construction, having its bar members 3a formed integrally with a body portion 6a.

The other reel member 2a is generally similar to the corresponding reel member of the reel shown in Figures 1 and 2. It comprises separately formed bar members 4a, alternately disposed to the bar members 3a of reel member 1a, mounted in openings in rotatable supporting member 12a. Bar members 4a are held in place in member 12a by means of set screws 13a. Said rotatable supporting member 12a is rigidly mounted on a bearing sleeve 14a by means of which it is journaled on frame member 5a for rotation about an axis disposed in the desired offset and inclined

relation to the axis of rotation of reel member 1a.

As already mentioned, reel member 1a is provided with a plurality of radial openings 17a of two different sizes. Such openings extend from points between the bar members 3a to internal grooves 22 formed in the inner wall of the longitudinally extending opening 21 in reel member 1a. Openings 16a in drive shaft 1a are so located that they conduct heated air or other suitable medium from the interior of said drive shaft to corresponding grooves 22 and thence through corresponding openings 17a to the exterior of the reel. The openings 17a vary in size according to groups, being larger adjacent the supported end of the reel.

The general construction of the reel shown in Figures 5 and 6 is similar to that of the reels described above; that is to say, it comprises two wholly rigid reel members 1b and 2b.

Reel member 1b comprises a plurality of spaced, longitudinally extending bar members 3b rigidly fixed to or formed integral with a body portion 6b mounted on hollow drive shaft 7b. Body portion 6b is provided with an interior chamber 15b which is closed off at the unsupported end of the reel by means of a plate 23 which is clamped in place by cap bolt 8b threaded into the end of drive shaft 7b. Said cap bolt 8b urges reel member 1b against a pin 9b passing through drive shaft 7b and projecting into grooves 10b formed in the end of said reel member 1b.

As in the preceding embodiments of the invention, reel member 2b comprises separately formed bar members 4b rigidly held in place in holes in supporting member 12b, as by set screws 13b. Supporting member 12b is provided with a bushing 14b by means of which it is mounted on frame member 5b. The latter is formed with its axis in offset and inclined relation to the axis of rotation of reel member 1b. The axis of rotation of reel member 2b coincides with the axis of frame member 5b, thus effecting the desired relation between the axes of rotation of the two reel members.

In the reel of Figures 5 and 6, the heating medium is supplied through hollow drive shaft 7b, being discharged into the interior chamber 15b of reel member 1b through openings 16b. A frusto-conical deflector 24 is associated with said drive shaft in such manner that it deflects a large portion of the air passing out of the openings 16b through the inclined openings 17b adjacent the supported end of the reel. Thus by means of the deflecting means 24, more heated air is passed through the inclined radially extending openings 17b adjacent the supported end of the reel than is passed through the radially extending openings 17b disposed toward the unsupported end of the reel.

In this embodiment of the invention, moreover, the bar members 4b of reel member 2b, which bar members are disposed between the bar members 3b of reel member 1b, are tapered toward the interior of the reel as shown so as to provide for an improved flow of the heated air from the openings 17b to the thread on the reel. Bar members 4b are so formed that the streams of heated air are directed toward the thread carried by the bar members of the reel with a minimum of turbulence and consequently with a minimum of heat loss. An efficient streamline flow of air to the thread is thus made possible.

In each of the several embodiments of the

invention hereinabove described, the greatest amount of heat is applied to the thread at a point where it has its highest moisture content, the amount of heat being thereafter decreased either progressively or non-progressively. Thread having a high moisture content can be safely heated to a higher temperature than can the thread having a low moisture content; consequently, if the invention were not employed, the low temperature to which the dried or partially dried thread could safely be heated would be also the maximum temperature to which the wet thread could be heated, with consequent low speed of drying. The present invention therefore makes for efficient, rapid continuous drying of the thread with no likelihood of its being damaged.

It will be understood that the above-described embodiments of the invention are illustrative only and that numerous modifications may be made therein without departing in any way from the spirit of the invention. For instance, thread-advancing thread store devices of other types than those illustrated may be employed. Further, the thread-advancing thread store device, whether of the type shown or other types, may be heated or cooled by other means than air passed therethrough in the manner described. It is also apparent that the present invention is not limited to the use of a temperature-changing fluid in treating thread per se, but may be employed in treating any strip material capable of being subjected to the processes or handled by the apparatus of the present invention.

It is intended that the patent shall cover, by suitable expression in the appended claims, whatever features of patentable novelty reside in the invention.

What is claimed is:

1. A thread-advancing reel of cantilever construction comprising a first reel member having a plurality of spaced longitudinally extending bar members; a second reel member mounted for rotation in offset and inclined relation to said first reel member having a plurality of spaced longitudinally extending bar members which interdigitate with those of the first reel member; a hollow member supporting the first reel member; a chamber in said reel member and around said hollow member, said hollow member being provided with conduits communicating with said chamber; openings extending through the wall of the first reel member between the chamber and the exterior of said reel member; and guide means within said chamber for directing a temperature-changing fluid admitted thereto by the hollow member toward the openings.

2. A thread-advancing reel of the character described in claim 1 in which said openings are flared toward the exterior of said first reel member.

3. A thread-advancing reel of the character described in claim 1 in which certain of said openings are inclined outwardly toward that end of the reel at which the thread to be treated is first applied.

4. A thread-advancing thread store device comprising two thread-manipulating elements which are disposed in offset and inclined relation to each other and cooperate to form a thread-bearing periphery along which thread is advanced; means for rotatably supporting said thread-manipulating elements; means associated with said supporting means for introducing a temperature-changing fluid into the interior of at least one of said thread-manipulating ele-

ments; and means in the last-mentioned thread-manipulating element for applying the temperature-changing fluid to the thread, said applying means being so constructed and arranged as to supply a greater quantity of said fluid adjacent the point at which the thread is first applied to the periphery of the thread-advancing thread store device than adjacent the point upon the periphery at which the thread is removed.

5. A thread-advancing thread store device of 10

the character described in claim 4 in which the applying means take the form of a plurality of conduits extending from the interior to the exterior of the thread-manipulating element, said conduits being of greater cross section adjacent the point at which the thread is first applied to the periphery of the thread-advancing thread store device than adjacent the point upon the periphery at which the thread is removed.
